UNITED STATES PATENT OFFICE.

IVAR F. WARME AND GEORGE FLUCK, OF SYRACUSE, NEW YORK, ASSIGNEES TO
CONTINENTAL CAN COMPANY, INCORPORATED, OF SYRACUSE, NEW YORK, A
CORPORATION OF NEW YORK.

CAN-END-FEEDING MECHANISM FOR CLOSING-MACHINES.

1,285,502.

Specification of Letters Patent. Patented Nov. 19, 1918.

Application filed August 10, 1916. Serial No. 114,255.

To all whom it may concern:

Be it known that we, IVAR F. WARME and GEORGE FLUCK, citizens of the United States, residing at Syracuse, in the county 5 of Onondaga, State of New York, have invented certain new and useful Improvements in Can-End-Feeding Mechanism for Closing-Machines, of which the following is a description, reference being had to the 10 accompanying drawing and to the figures of reference marked thereon.

The invention relates to new and useful improvements in can end feeding means for closing machines, and more particularly to 15 a closing machine having a rotating seaming head carrying seaming rolls such as shown for example in the patent granted to Ivar F. Warme, March 16th, 1915, No. 1,132,291.

20 An object of the invention is to provide means for raising the stack of can ends, so as to release the lowermost can end to facilitate the removal of the same from the stack by the can end pusher.

25 A further object of the invention is to provide a device of the above character wherein the stack-raising mechanism is adjustable for different sized can ends.

These and other objects will in part be 30 obvious, and will in part be hereinafter more fully disclosed.

In the drawings, which show by way of illustration one embodiment of the invention,—

35 Figure 1 is a plan view showing a part of a closing machine with a stack-holder and can-end-feeding mechanism attached thereto;

40 Fig. 2 is a sectional view through the stack-holder and the supporting bracket therefor, showing a portion of the pusher and a portion of the slideway for the can ends;

45 Fig. 3 is a sectional view through the stack-holder, showing the stack-raising device and the cam for operating the same;

Fig. 4 is a side view of the stack-holder and the stack-raising device;

50 Fig. 5 is a detail showing the stacked can ends in the stack-holder;

Fig. 6 is a view showing the stack-raiser moving forward and releasing the lowermost end; and

Figs. 7 and 8 are sectional details on lines 7—7 and 8—8 respectively, of Fig. 3. 55

The invention is applied to a can-closing machine having a rotating seaming head beneath which the filled cans are fed. Also beneath this head is a supporting ring having a seat for the can end, and the filled can 60 is raised so as to engage this can end. The can end is seated in the filled can, after which it is raised and presented to a rotating chuck and seaming rolls carried by the rotating chuck coöperate in forming a double seam for joining the can end to the can body. A machine of this type is shown in the patent above referred to. 65

Adjacent the seaming head is a stack-holder consisting of a supporting base 1 carrying a series of rods 2, 2. The ends are stacked between these rods. The supporting base is carried by a bracket 3, which is bolted to the seaming head and extends laterally at one side thereof. This bracket 70 carries the ring which seats the can end beneath the seaming head. The can end seat on the ring is indicated at 4 in Fig. 1 of the drawings. 75

The bracket 3 is provided with a recess 80 in the longitudinal center line of which is in the form of a segment of a circle. This recess extends from the seating ring 4 to a point underneath the stack-holder. The bracket 3 is also provided with a recess in 85 which reciprocates a pusher 5. This pusher 5 has a hardened plate 6 secured at the forward end thereof, and this hardened plate engages a can end underneath the stack-holder and forces it along the recess under 90 the seaming head. The pusher 5 is reciprocated by an arm 6^a, which is oscillated from the main shaft of the machine. Means is provided for disconnecting the pusher from the reciprocating arm, so that when 95 there is no filled can fed underneath the seaming head, then no can end will be fed from the stack on to the can end seat. This no-can-no-end feed is well known in the art, and has not been illustrated. 100

Associated with this can end feeding mechanism is a stack-raising device. This stack-raising device is in the form of a slide 7, which moves back and forth in a bracket 8, which in turn is bolted to the 105 bracket 3. The slide 7 has a hardened plate

9 at the forward end with an upwardly and backwardly beveled face 10. This beveled face 10 forms a separating lip 11, adapted to pass between the can ends in the stack, separating the lowermost can end from the remainder of the stack, as clearly illustrated in Figs. 5 and 6.

In Fig. 5, the can ends are indicated at E and they are stacked one upon the other. In Fig. 6 the slide is moved forward and the lip 11 has passed between the two lowermost can ends and has lifted the stack from the lowermost can end, so that the pusher may engage this lowermost can end and move it forward underneath the seaming head.

The slide 7 is reciprocated by a rocker arm 12. This arm 12 is pivoted at 13 to the bracket 8. The rocker arm 12 has a projecting lug 14 and a spring 15 bears against this projecting lug. The spring 15 is housed in the projecting arm 16.

The slide 7 is connected to the rocker arm 12 in the following manner: Said slide 7 is connected to a plate 17. Said plate 17 has an upstanding forked ledge 18, which receives a headed bolt 19. The said headed bolt is cut away to form a cylindrical portion 20, which extends between the arms of the fork. This headed bolt 19 is threaded at 21 and the threaded section engages the slide 7.

The plate 17 is secured to the rocker arm 12 by a bolt 22, which extends through the arm of the rocker and up through the plate 17, and also up through the slide 7. The slide 7, however, has a slot 23 extending lengthwise thereof through which the bolt 22 extends, which permits the slide to be adjusted by the turning of the headed bolt 19. It will readily be seen that by turning the headed bolt 19, the position of the slide 7 may be shifted relative to the operating rocker arm.

The rocker arm is provided with a roller 24 which engages a cam 25 carried by a shaft 26, mounted in suitable bearings and operated from the main shaft of the machine. This cam 25 is so timed as to move the stack-raising device forward to raise the stack to release the lowermost can end just before the pusher engages the lowermost end for carrying it forward underneath the receiving head.

The forward movement of the stack-lifting device is brought about through the action of the spring which prevents the jamming of the can ends in any way whatever as the spring is not strong enough to injure them, although it will raise the stack in the manner above described. The stack-raising

device is returned to idle position by the cam-engaging roller 24.

From the above description, it will be apparent that we have provided a stack-raising device operating in proper timed relation to the reciprocations of the pusher which carries the can ends forward underneath the seaming head. The stack-raising device lifts the stack from the can end which is to be moved forward. This prevents any scraping of the can ends which are drawn from the stack and greatly increases the efficiency of the can-end-feeding mechanism.

It is obvious that minor changes in the details of construction may be made, without departing from the spirit of the invention as set forth in the appended claims.

Having thus described our invention, what we claim as new and desire to secure by Letters Patent, is:—

1. A can-end-feeding mechanism for can closing machines including in combination, a stack-holder, a pusher for engaging the lowermost can end in the stack-holder for moving the same forward underneath the seaming head of the closing machine, and a stack-raising mechanism including an oscillating rocker arm, a slide operated by said rocker arm, said slide having a separating lip adapted to separate the lowermost can end from the stack, a spring for moving the rocker arm for carrying the slide forward to separate the lowermost can end from the stack, and a cam for moving the rocker arm to retract the slide.

2. A can-end-feeding mechanism for can closing machines including in combination, a stack-holder, a pusher for engaging the lowermost can end in the stack-holder for moving the same forward underneath the seaming head of the closing machine, a stack-raising mechanism including an oscillating rocker arm, a slide operated by said rocker arm, said slide having a separating lip adapted to separate the lowermost can end from the stack, a spring for moving the rocker arm for carrying the slide forward to separate the lowermost can end from the stack, a cam for moving the rocker arm to retract the slide, and devices whereby the connection between the slide and the rocker arm may be adjusted for different sized can ends.

In testimony whereof, we affix our signatures, in the presence of two witnesses.

IVAR F. WARME.
GEORGE FLUCK.
